CLOSURE SEALING DEVICE

Charles H. Wetzel, Wayne, Pa., assignor to Wayne Iron Works, Wayne, Pa., a corporation of Pennsylvania

Application September 16, 1954, Serial No. 456,483

1 Claim. (Cl. 20—68)

This invention relates to closure members and more particularly to a new and improved sealing means for use on sliding, folding or swinging closure members of many different kinds such as partitions, doors, windows, casements, etc. The sealing means of this invention is automatically effective to seal off or close the clearance space between the lower edge of the closure member and the confronting floor or other surface when the closure member itself is moved to closed position.

Conventional closure sealing devices involve complicated details and arrangements of parts, and/or require precise location and alignment with respect to the closure member with which they are associated. In contradistinction thereto, the closure-sealing means of this invention is simple in construction and can be mounted on a closure member without necessity for accurate location and alignment with respect thereto. Due to the simplicity of construction, the closure sealing means of this invention is economical to produce and easy to maintain.

It is accordingly an object of this invention to provide an improved closure member sealing means which is automatic and foolproof in operation, simple in construction and durable in use.

A further object of this invention is to provide a novel closure member sealing means which can be mounted without necessity for accurate setting thereof on the closure member.

Another object is to provide closure-member sealing means having a high degree of self-adjustability to uneven or untrue floor conditions.

Further objects and advantages will become apparent from the detailed description which follows.

The novel sealing means which forms the present invention will be described with reference to its use on a folding panel partition. The folding panel partition shown in the drawing is of conventional type used to divide a large room or enclosure into two smaller ones. This partition is of the "mono-fold" type in which the partition when folded is stacked on one side of the room, and when extended travels across the room to the opposite wall. The invention applies equally to the "duo-fold" type of partition, in which the partition is made in two parts which when folded, stack respectively on opposite sides of the room, and when extended travel across the room to meet in the mid area, the one then acting as an abutment for the other.

In the drawing:

Fig. 1 is a side elevational view of one panel of a folding panel partition and a portion of another panel, these panels being provided with the improved sealing means of this invention;

Fig. 2 is a cross-sectional view taken on line 2—2 of Fig. 1;

Fig. 3 is a side elevational view showing the sealing means in fully closed position;

Fig. 4 is a fragmentary side elevational view illustrating the self-adjustability of the sealing means to meet abnormal conditions in the related structure;

Figs. 5 and 6 are fragmentary sectional elevational

2

views illustrating modifications within the scope of the invention;

Fig. 7 is a similar view showing still another modification, and

Fig. 8 is a sectional view on the line 8—8, Fig. 7.

Reference numeral 1 refers to the outer end panel of the partition which leads when the partition is being extended. This leading panel is pivotally connected to intermediate panel 2 by means of hinges one of which is shown at 2a in Fig. 1. Fig. 1 shows these panels at a point in their movement toward closed position and shortly before the sealing means of this invention becomes automatically effective. Each of the panels is provided with inset members 3 disposed on opposite sides of the base of the panel to form therebetween a housing space for a sealing strip. Except for certain details in the length and shape of the sealing strip which will be pointed out below, the sealing means for each panel is the same. Accordingly, the sealing means will be described at this point with respect only to the outer end panel.

The sealing means comprises a sealing strip 4, coil springs 5, and means for automatically moving the sealing strip downwardly into engagement with the floor 6 upon movement of the panels to closed position. The sealing strip 4 can be of any desired material and normally lies below and parallel with the lower edge of the bottom rail of the panel framework. This strip 4 is provided with a portion 7 which normally projects horizontally past the outer vertical or leading edge of the panel. Except when the panel is in closed position, the sealing strip 4 is resiliently supported above the floor 6 by means of coiled tension springs 5. Downward movement of the sealing strip 4 when the panel is moved to closed position is effected by flexible leaf spring cams 8 in cooperation with their respective follower rollers 9. The cams 8 are secured to the upper edge of the sealing strip 4 by any suitable means. Brackets 10 mount the rollers 9 and are secured to the bottom of the panel between the members 3. During the final movement of the panel to closed position, projecting portion 7 of the sealing strip 4 will engage wall 11 and the wall will then constitute a stop interrupting the movement of the strip with the panel during the final movement of the latter to fully closed position. The resulting relative movement between the panel and the strip will cause the rollers 9 to advance onto the inclined portions of the respective flexible cams 8 and will thereby force the sealing strip downwardly toward the floor 6 against the tension of the springs 5. At the fully closed position of the panel, the vertical edge of the latter will have engaged the wall 11 and the lower edge of the sealing strip 4 will lie in engagement with the floor 6, see Fig. 3, the space between the floor and panel being thereby effectively sealed.

A more detailed consideration of the operation of this improved sealing means will disclose one of the more important advantages of this novel mechanism. Referring to Fig. 1, the initial movement of the sealing strip 4 after projecting portion 7 engages the wall 11 is downward. This continues until the sealing strip engages the floor, at which time no further movement of the strip downwardly is possible. In certain conventional sealing strip constructions, the length to which portion 7 projects beyond the adjacent vertical edge of the panel must be accurately dimensioned in order that the outer extremity of portion 7 may move into alignment with the vertical edge of the panel precisely at the time the lowermost edge of the sealing strip engages the floor. Otherwise, either the sealing strip will not engage and seal off all of the space between the closure member and the floor, or the said vertical edge of the panel will not meet the wall 11. Such is not the case with the sealing means of this invention.

After contact between the lower edge of the sealing

strip and the floor, the panel may still move to the left with respect to the strip due to the flexibility of the springs 5 and cams 8. Under these conditions, the coil springs 5 will continue to extend and the inclined portions of flexible cams 8 will be flexed downwardly by the rollers 9 until the edge of the panel engages the wall. It will be apparent therefore that neither the longitudinal position of the sealing strip with respect to the panel at the open position nor the height of the lower edge of the panel with respect to the floor is critical in accommodating the sealing means of this invention to any particular installation.

Another desirable characteristic resides in the high degree of inherent self-adjustability in the device. It is not necessary, for example, that the lower edge of the panel be parallel to the floor 6, since, as shown in Fig. 4, the strip 4 will automatically assume a position in its housing and by differential action of the resilient cams 9, in correspondence with the floor surface.

Any number of intermediate panels such as that denoted by reference numeral 2 in Figs. 1 and 3 may be provided in addition to the inner end panel (not shown). Each panel is provided with a separate sealing strip, and all of the strips move into abutting, longitudinally aligned relation with each other when the panels are moved from their folded positions to their unfolded and coplanar positions. With all of the sealing strips in abutting and substantially longitudinally aligned relation at the position of the panels shown in Fig. 1, longitudinal movement of the sealing strip 4 on panel 1 due to engagement of projecting portion 7 with the wall 11 is in turn transmitted to the other sealing strips of the respective panels. In the present instance, the length of the sealing strip for each of the intermediate panels is equal to the length of the respective intermediate panel to which it is attached, and normally lies within the confines of said panel.

It is apparent that the closure member sealing means disclosed herein is equally effective for use on swinging and sliding closure members. Also, this improved closure sealing means can be utilized on single or plural sectioned doors, windows, casements, etc. A reversal of the relative positions of the rollers and coating cams will not offset the operating characteristics.

The invention is not limited to the particular construction described above and may be embodied in other forms without departure from the principle of the invention. In the embodiment of Fig. 5, for example, the flexible cam 8 of the previously described embodiment is replaced by a rigid cam element 12. The roller or cam follower 13 is mounted in this case upon a bracket 14 which is pivotally secured at 15 to the bottom of the panel, the panel in this instance being indicated by the reference numeral 16. The bracket 14 is depressed by a coil spring 17 which normally holds the free end of the bracket against a stop 18, the follower 13 being engaged with the cam 12. When the sealing strip 19 to which the cam 12 is secured, is forced to the right as viewed in Fig. 5 and as described in connection with the embodiment of the invention disclosed above, the cam 12 reacting with the roller 13 will force the sealing strip downwardly toward and against the floor surface 20. If the strip 19 engages the floor before its longitudinal movement has been completed the roller 13 and its bracket 14 may be upwardly about the pivot 15 and against the pressure of the spring 17 which contracts to relieve the undue strain which otherwise would fall upon the elements of the device.

The embodiment of Fig. 6 corresponds more closely to that disclosed in Figs. 1 to 3 inclusive in that in this case the cam 21 is resiliently supported in normal operative position. The cam support in this instance takes the form of a coil spring 22 which reacts with the sealing strip 23 and against the underside of the came 21, the opposite end of the cam being hinged at 24 to a bracket 25 attached to the sealing strip. The follower roller 26 in

5 this case is supported in a bracket 27 rigidly secured to the bottom of the panel 28. It will be apparent that the spring 22 prevents undue strain being imposed upon the elements in the event that the sealing strip 23 engages the floor or other obstruction before its longitudinal movement to the right has been completed.

In Figs. 7 and 8 I have shown a somewhat different arrangement comprising a rigid cam element 29 attached to the upper part 30 of a sealing strip indicated generally by the reference numeral 31. The follower 32 is journaled in a bracket 33 rigidly secured to the bottom of the panel 34. Longitudinal movement of the sealing strip 31 to the right as viewed in Fig. 7 will result in a reaction between the cam and its follower which will force the strip downwardly toward the floor surface indicated by the reference numeral 35. In the event that an obstruction or the floor surface 35 itself interrupts the downward movement of the sealing strip before the longitudinal movement of the strip has been completed, a lower longitudinal portion 36 of the strip which is adjustably secured to the upper portion 30 will move upwardly against the pressure of springs 37-37 which normally hold the portion 36 of the strip in a relatively extended position. The lower portion 36 of the strip is attached to the upper portion 30 in the present instance by means of a link 38, and the maximum extended position of the lower portion 36 of the strip is established by tie bolts 39 which extend upwardly from the section 36 of the strip through apertures 40 in the upper strip portion 30 in which apertures the bolts are freely slideable. Nuts 41 on the upper ends of the bolts engage the upper edge of the strip section 30 and act as stops to limit the extension of the lower section 36 of the strip by the springs 37.

35 I claim:

40 A sealing device for folding partitions, doors and like closure members, said device comprising a sealing strip mounted on the closure member with freedom to move both longitudinally and transversely relative to said member between a normal retracted inoperative position and an extended sealing position, a resilient cam assembly including a cam element and co-active rolling follower mounted one on the closure member and the other on the sealing strip for actuation in response to the said longitudinal movement of the strip to displace the strip transversely to the extended position, said cam assembly comprising a resilient leaf spring having a free end portion inclined to the longitudinal axis of the strip and yieldable in direction normal to said axis under pressure of the follower for relieving an undue pressure on the assembly when the displacement movement of the strip is interrupted before completion of the longitudinal movement of the strip, and resilient means operatively connected to the member and strip for supporting the strip in the retracted position, said means being biased by longitudinal displacement of the strip from the normal retracted position so as to exert forces tending to draw the strip both longitudinally and transversely from the extended position.
